UNITED STATES PATENT OFFICE.

REED W. HYDE, OF SUMMIT, NEW JERSEY, ASSIGNOR TO DWIGHT AND LLOYD SINTERING COMPANY, INC., OF NEW YORK, N. Y., A CORPORATION OF DELAWARE.

IGNITER FOR SINTERING MACHINES.

Application filed May 21, 1927. Serial No. 193,134.

This invention relates to a sintering machine and more particularly to an igniting apparatus for initiating combustion in the layer of material to be sintered.

5 In sintering any material, the operation is started by igniting the combustible material at the surface of the charge, as by applying a flame thereto for a brief period of time, after which combustion is propagated 10 through the layer by the air currents drawn therethrough. The ignition should preferably be complete over the entire surface, uniform, rapid and superficial, while avoiding fusing the material.

15 This invention relates specifically to means for igniting the charge by heat thrown on the surface from an electrically heated ignition device placed above and spaced somewhat from the surface of the charge. It provides 20 easily controlled means for effecting complete, uniform, rapid, surfaced ignition without the undesirable features of drying the underlying portion of the charge, overheating and fusing the surface, unevenness of ignition and similar faults. It eliminates the 25 constant attention required by oil, coal or wood fired igniters, and the necessity for compressed air, and expensive piping and storage and pumping systems required by oil 30 or gas. Once adjusted, it continues without further attention so long as current is supplied.

The invention also consists in certain new 35 and original features of construction and combinations of parts hereinafter set forth and claimed.

The invention will be described in connection with the well known Dwight and Lloyd 40 straight line continuous sintering machine, but may obviously be adapted to other types of sintering apparatus.

An electrical resistor capable of developing 45 a high degree of heat, which may be formed of a coil of resistance wire, a series of resistance blocks, or other suitable resistor material, is secured to a backing plate such as asbestos lined metal, tile or other non-combustible insulating material, or may be supported on a metal backing plate by suitable

spaced insulators. This is secured to a suitable framework and supported a short distance above the surface of the charge in the sintering apparatus so that the heat developed will be directed and reflected onto the 50 surface.

55 Although the novel features which are believed to be characteristic of this invention will be specifically pointed out in the claims appended hereto, the invention itself, as to its objects and advantages, the mode of its 60 operation and the manner of its organization, may be better understood by referring to the following description taken in connection with the accompanying drawing forming a part thereof, in which like reference characters 65 have been used to denote like parts in the various figures. Since such illustration is, however, primarily for purposes of disclosure, it will be understood that the structure and the method of operation thereof 70 may be modified in various respects without departing from the broad spirit and scope of the invention.

75 One embodiment of the invention has been shown for purposes of illustration in the accompanying drawing, in which

Fig. 1 is a broken elevation of a portion of a sintering machine constructed in accordance with the invention,

Fig. 2 is a section taken on the line 2—2 of 80 Fig. 1,

Fig. 3 is a detail view of a resistor element which may be employed and

Fig. 4 shows a modified form of resistor element.

85 In the following description and in the claims the various parts of the apparatus and details of the invention will be identified by specific names for convenience, but they are intended to be as generic in their application 90 as the art will permit.

95 Referring more particularly to the drawings, pallets 10 may be elevated by sprocket wheel 11 and propelled thereby along track 12, passing first under the hopper 13 and receiving the ore to be sintered, then over a dead plate 14 and windbox 15, where the sintering operation takes place. Plate 14 prevents

leakage of air into windbox from beneath the pallets.

The igniter consists of a metal framework 20 to which is attached a sheet of asbestos mill 5 board 21 on which, in turn, is secured a coil of resistor wire 22, the ends of which may be connected to a suitable source of current. The igniter, which has a width substantially 10 the same as that of the pallets may be hung by supporting brackets, and should preferably be adjustable vertically and horizontally. A shield or hood 16 for the igniter, having a slot 24 in the edge near the windbox, serves to keep off draughts or wind which 15 might interfere by causing loss of heat, but permits entrance of air where such is desired.

The igniter should be supported in such a location that it heats the top surface of the ore charge in the pallets to ignition temperature, that is to a temperature at which combustion of sulphur, carbon or other combustible in the charge can take place, this heating being accomplished mainly before the ore layer reaches a point in its travel where appreciable volumes of air are drawn there- 20 through, and then preferably continuing for a brief distance thereafter.

It is desired to heat the surface approximately to ignition temperature while little or 30 no air currents are passing therethrough, and then to continue this heating for a short time while air is being supplied. This procedure avoids the great loss and waste of heat which would occur were air drawn thru the layer 35 during the entire warming up and heating period, but insures the surface being maintained at ignition temperature when the cold air blast first strikes it and until the combustible constituents commence to burn.

40 The ore charge first comes under the influence of comparatively light induced air currents at a point shortly before it reaches the beginning of the windbox, the air being drawn through it as indicated by the arrows. 45 The exact point depends on various conditions, including degree of suction and permeability of charge. At the windbox itself, the air currents are much more violent. Hence the most favorable location of the 50 igniter is most easily determined, in any given case, by trial. As shown in Fig. 1, it is placed with its forward end slightly beyond the beginning of the windbox.

55 Since the degree of heat required for ignition is a function of the particular material being sintered, and varies widely with different materials, it is obvious that it is a factor that must be considered in applying an igniter in any individual case. Various 60 means of adjusting the heat are available such as, varying the length of the igniter, which in connection with the rate of travel of the pallets determines the time the ore is exposed to the heat. The spacing of the 65 resistor elements or the strength of the elec-

tric current may also be controlled for this purpose. Preferably the variable factors are so coordinated that the charge is subjected for only a brief period to a sufficiently intense heat to raise the surface to the 70 ignition point, without drying out the underlying portions of the charge, fusing the top surface, or causing other undesirable results.

In operation, the current being turned on and the pallets moving forward, as the charge 75 slowly passes under the igniter the surface is heated to the ignition point by the heat radiated and reflected down on it from the resistor elements. Then, while this heating is still maintained, relatively light air currents 80 are drawn through the charge which initiate combustion of the combustible ingredients. These air currents should at first be so light as not to chill the surface below the ignition point. This combustion raises the tempera- 85 ture still more, so that when the ore reaches the region of more violent air currents combustion is progressing actively, and proceeds down through the layer, effecting sintering of 90 the charge.

95 Fig. 4 shows another form of igniter, having a curved shape, in order to reflect or focus the heat on the surface of the charge. This igniter may be located at a greater distance above the surface of the charge, without loss of heating efficiency, and thereby avoid damage due to particles of hot charge flying up into the air when ignited (as happens when sintering certain kinds of materials) and becoming attached to and possibly short circuiting the resistor elements.

100 All forms of the igniter are so constructed as to prevent currents of air from passing between or among the resistor heating elements. This avoids waste of heat in heating the air currents before the charge has reached ignition 105 temperature, and also insures longer life to the resistor, since air currents would tend to oxidize them and cause them to burn out more, rapidly. Also no plate or other obstruction 110 is inserted between the resistor heating elements and the surface to be heated, thereby avoiding loss and wastage of heat.

115 The igniter is so constructed and located as to insure most efficient and economical use of the heat developed. The surface of the charge is heated to a desired temperature before air currents begin to pass through the layer under the influence of the suction means and this heat is maintained while relatively 120 light air currents pass through the charge to start combustion in the surface of the layer. When the more violent air currents are passing through the layer it will have passed beyond the igniter, so that ignition heat will 125 not be wasted in warming up these large volumes of air. The heat is concentrated on the charge, where it will do the most good.

130 While this invention has been described in connection with the continuous type of sinter-

ing machine, it will be obvious that it is equally applicable to other types without departing from the spirit of the invention. For example it may be applied to stationary sintering pans by making the igniter of a size corresponding with the surface area of the pan, and mounted on a movable frame. In operation, the pan being charged with material to be sintered, the igniter may be set over the pan and the electric current turned on. After a brief interval when the combustible ingredients in the surface of the charge have been heated to ignition temperature, the suction device may be started and air currents drawn through the charge after which the electric current may be turned off, the igniter removed and the sintering operation continued.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. An electric ignition device comprising a resistance element capable of being heated to a high temperature by passage of an electric current therethrough and means for reflecting the heat developed thereby onto the surface to be ignited and for preventing circulation of air currents about the resistance element, and means for shielding a portion of the surface to be ignited from air currents and permitting light air currents to pass over another portion of said surface.
2. A resistance device comprising a series of resistance elements arranged in parallel relationship and adapted to extend over a substantial area and means for reflecting heat developed thereby onto the surface to be ignited and for preventing circulation of air currents about the resistance elements, and means for shielding a portion of the surface to be ignited from air currents and permitting light air currents to pass over another portion of said surface.
3. A resistance device comprising a plurality of resistance elements arranged in parallel relationship and extending over a substantial area, an adjustable support for said elements and a reflector for reflecting and focusing heat upon the material being ignited and for preventing circulation of air currents about the resistance elements.
4. In combination with a sintering machine including a plurality of pallets, a wind box, means for passing successive pallets thereover, and an electrical ignition device adapted to reflect heat upon the charge in said pallets and to ignite the surface thereof prior to the passage over said wind box.
5. In combination with a sintering machine including a plurality of pallets, a wind box and means for passing successive pallets thereover, an electrical ignition device adapted to radiate heat onto the surface of said pallets for igniting the material therein and acting upon said material before it passes
6. A sintering machine having a plurality of movable pallets, said pallets having perforate bottoms, electrical means for igniting combustible materials contained in said pallets, means for passing a comparatively small amount of combustion supporting gases therethrough for initiating combustion and means for passing a comparatively large volume of said gases therethrough for completing said combustion after ignition.
7. In combination with a sintering machine, a plurality of movable pallets, means for reflecting a sufficient amount of electrically developed heat upon said pallets to bring the surface of the layer of materials therein to ignition temperature, means for thereafter passing a comparatively light current of combustion supporting gas through said material for initiating combustion, and means for continuing the application of heat thereto until combustion is well under way and means for passing a comparatively large volume of said gas therethrough for completing the combustion after ignition.
8. In a sintering machine, a plurality of movable pallets having perforate bottoms, an ignition device comprising an electric resistance covering a substantial area, and adjustably supported above the surface of the material contained in said pallets, to radiate heat onto said surface, a wind box and means for passing strong currents of air through said pallets while over said wind box and means for successively passing said pallets under said ignition device and over said wind box.
9. In combination with a sintering machine a plurality of movable pallets, means for reflecting a sufficient amount of electrically developed heat upon said pallets to bring the surface of materials therein to ignition temperature, means for passing a comparatively light air current through said material initiating combustion, means for continuing the application of heat thereto until combustion is well under way and means for passing a comparatively large volume of air currents therethrough for completion of combustion.
10. In combination with a sintering machine including a plurality of pallets, a wind box and means for passing successive pallets thereover, and electrical ignition device adapted to radiate heat onto the surface of said pallets for igniting the material therein and acting upon said material before it passes

over said wind box whereby air currents are largely prevented from passing through said pallets during the ignition period.

11. A sintering machine having a plurality of movable pallets, said pallets having perforate bottoms, electrically heated means for igniting combustible materials contained in said pallets, means for passing a compara-

tively small amount of air therethrough for initiating combustion and means for passing ¹⁰ a comparatively large volume of air therethrough for completing said combustion.

In testimony whereof I have hereunto set my hand.

REED W. HYDE.
